UNITED STATES PATENT OFFICE.

DAVID E. WILLIAMS, OF CLEVELAND, OHIO; SARA E. WILLIAMS ADMINISTRATRIX OF
SAID DAVID E. WILLIAMS, DECEASED.

GATE FOR DRY DOCKS, LOCKS, AND THE LIKE.

Application filed July 28, 1920, Serial No. 399,618. Renewed November 30, 1923.

To all whom it may concern:

Be it known that I, DAVID E. WILLIAMS, a citizen of the United States, and a resident of Cleveland, county of Cuyahoga, and 5
6 State of Ohio, have invented a new and useful Improvement in Gates for Dry Docks, Locks, and the like, of which the following is a specification, the principle of the invention being herein explained and the best mode 10
11 in which I have contemplated applying that principle, so as to distinguish it from other inventions.

The present improvements relate more particularly to operating means for use in 15
16 connection with gates of the so-called pontoon or caisson type, such as are used to close dry docks, and also, in certain instances, canal locks and the like. The objects of the invention include the provision 20
21 of operating means whereby such a gate may be easily and quickly swung into position either to open or to close the dock or lock; the disposition of the gate when open, so as to not interfere in any way with the movement 25
26 of a vessel through the gateway; and the location of the control of the operation of the gate wholly on shore.

To the accomplishment of the foregoing and related ends, the invention, then, consists of the means hereinafter fully described and particularly pointed out in the claims, the annexed drawing and the following description setting forth in detail certain mechanism embodying the invention, such 30
35 disclosed means constituting, however, but one of various mechanical forms in which the principle of the invention may be used.

In said annexed drawing:—

Fig. 1 is a plan view, more or less diagrammatic, of a lock, with gate of the type above referred to, for closing same, and my present improved operating means for opening and closing said gate; Fig. 2 is a similar transverse section through the gate, showing same as in closed position; Fig. 3 is a side elevation, on a larger scale, of the main element entering into the construction of the operating means; and Fig. 4 is a side elevation and part section of a detail of such means, the plane of the section being indicated by the line 4—4, Fig. 3.

As previously indicated, my present improved operating means are designed for

use in connection with the so-called caisson type of gate, which, in construction, is a 55 hollow vessel 1, shown in cross-section in Fig. 2, adapted to be supplied with water ballast, whereby its buoyancy may be varied. In other words, when the gate is to be swung either open or shut, the ballast is lightened 60 sufficiently by pumping out water from the interior of the gate to cause the same to float, while when closed the amount of ballast is increased until the gate settles under the increased weight thus provided, and 65 rests solidly on the ledge 2 of the dock or lock 3, the ends 4 of the gate at the same time resting against vertical abutments 5 formed in the side walls of the dock. The handling of a gate of this sort, while apparently simple, has heretofore involved considerable difficulty, owing to the lack of any efficient means for controlling its movements from open to shut position, and vice versa, a system of cables being required, or 70
75 else a tug, in order to pull the gate about.

According to my present invention, I provide a longitudinally extending track 6 on the upper surface or deck of the gate, such track being conveniently formed of two 80 angles 7, spaced apart so as to provide in effect a groove or channel closed at each end, such channel terminating short of the end of the gate, as shown in Fig. 1. Movable lengthwise of this channel-track 6 is a 85 carriage or trolley 8 that is guided in such movement by means of rollers 9 disposed about vertical axes so as to bear against the upstanding flanges of the respective channels 7, while rollers 10 on horizontal axes 90 support the weight of the carriage in the channel groove. Electrically operated brake shoes 11 are provided adjacent each such roller 10 so as to frictionally lock the same when desired, and thus effectively retain the 95 trolley 8 against movement in the channel track when desired. Rising vertically from the trolley 8 is a spindle 15 that is rotatably journaled, as well as vertically movable, in a bearing 16 in the outer end of a swinging 100 lever 17, rotatably supported on a pedestal 18 on one of the side walls of the dock 3 or at some other convenient point on the shore. The inner end of this lever extends beyond the pedestal, and has attached thereto a 105 suitable counterweight 19, a ball bearing 20

being provided to facilitate its movement about the axis provided by the pedestal, as also a brake band 21 whereby it may be locked to such pedestal and held against such rotative movement when desired.

It will be observed that the respective ends of the gate are symmetrically beveled, and that from the beveled faces thus provided there respectively project screw propellers 22, 23, 24 and 25 (see Fig. 1), the shafts or axes of said propellers lying at an angle to the longitudinal axis of the gate. It will be observed that the beveled faces on the inwardly directed side of the gate, when the latter is in closed position, extend inwardly beyond the side walls of the dock, and that the corresponding propellers 22 and 23 are located so as to clear such side walls; also that the propellers 24 and 25 on the outwardly directed beveled faces are symmetrically disposed with respect to propellers 22 and 23. These propellers are designed to be operated electrically, a separate electric motor, as shown in Fig. 2, where the motors 22^a and 24^a for driving propellers 22 and 24, respectively, appear in diagrammatic form, being directly connected with each, although if desired a fewer number of motors may be employed, and suitable clutches and gearing interposed between same and said propellers, so that the latter may be individually operated as hereinafter described. For the purpose of operating said propellers, assuming the same to be thus driven by independent motors, suitable electrical connections are carried by means of a cable 26 from the shore along the lever 17 to the trolley 8, and thence through a series of contact shoes 27 to a corresponding series of contact strips 28 disposed alongside of and parallel with the channel groove 6 in which said trolley moves. These strips, as well as the contact shoes in question, are covered over by means of a housing 29, save on the side adjacent the channel track which is open to allow the supporting bracket 30 for the shoes the necessary freedom of movement, as the trolley travels back and forth in said channel track.

It is not deemed necessary to show in detail the connections from the contact strips 28 to the separate motors or other driving means provided for independently operating the propellers any more than to show such driving means in detail. It will be understood that the electrical connections carried through cable 26 to the shore are there controlled by suitable switches on a control panel or box (likewise not shown), whereby current may be supplied to start and stop the operation of the individual propellers, at the discretion of the operator.

The manner in which the gate is operated by the above described means may now

be briefly set forth. Assuming the gate to be in closed position shown in full lines in Fig. 1, the ballast is of course first lightened sufficiently to permit said gate to float, this being accomplished by means of a suitable pump or pumps on the gate, preferably electrically operated from the control station on the shore, in the same fashion as the propellers are operated. With the gate in floating condition, the operator thereupon starts propellers 22 and 23, the lever arm 17 being left freely swinging. As a result the gate will move bodily outwardly from the dock in a more or less direct line, i. e. parallel with the axis of the dock, the trolley 8 being thus brought to the right-hand end of the channel track 6, as the lever swings outwardly with the gate. The position of gate and lever at this stage is that marked "A" in Fig. 1.

Thereupon the trolley is locked by setting the brakes 11, and propellers 23 and 25 are operated, the lever 17 still freely swinging about pedestal 18. As a result the gate tends to move transversely of the axis of the dock, and at the same time is swung outwardly until position "B", Fig. 1, is reached. Upon now loosening the trolley in the channel groove, and setting the brake 21 which prevents further swinging movement of the lever 17, propellers 23 and 25 being continued in operation, and propellers 22 stopped the gate moves longitudinally of its own axis until the trolley reaches the left-hand end of channel track 6; whereupon the lever 17 is again left free to swing, propellers 24 and 25 are operated, and the gate thus brought successively into positions "C" and "D". In such last mentioned position the gate rests in a position the counterpart of that occupied when closing the dock, but entirely to the right of the latter, a suitable pocket 31 being provided alongside of the dock for the reception of the gate.

When it is desired to close the gate, the several steps just described are repeated, but in more or less reverse order, or in other words by setting in motion the proper propellers, and properly controlling the setting of the brakes 11 on the trolley and of the brake band 21 on the pedestal, the gate is brought successively into positions "C", "B" and "A", and finally in fully closed position, after which ballast is added sufficient to again seat the gate in place.

It will be understood that it is not necessary of course to swing the gate entirely into position "D" in order sufficiently to clear the dock for the entrance or removal of a vessel therefrom; but that the gate may be swung into a variety of different positions from those illustrated and still operate satisfactorily for every purpose. By means, however, of the system of control disclosed in the drawings and hereinbefore

described, it will be obvious that such movement of the lock is effected wholly from the shore station, and that a single operator, with the necessary electrical switches conveniently grouped, can accomplish the opening and closing of the gate in desired fashion.

It will be also understood that the arrangement of propellers, two at each end of the gate with their axes inclined at similar angles, less than a right angle, to the longitudinal axis of such gate, may be found advantageous, even where other means than lever 17 and trolley 8 are employed to control the movement of the gate, vice versa, such lever and trolley will afford a satisfactory agency for such control irrespective of whether the dock be shifted in position by means of such propellers or otherwise, for example, by means of cables operated from on shore, or the dock.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. The combination with a gate of the type in question, of a track extending longitudinally of said gate, and a lever pivotal about a fixed station, the free end of said lever having movable connection with said track.

2. The combination with a gate of the type in question, of a track extending longitudinally of said gate, a lever pivotal about a fixed station, the free end of said lever having movable connection with said track, and means adapted to lock said lever against pivotal movement when desired.

3. The combination with a gate of the type in question, of a track extending longitudinally of said gate, a lever pivotal about a fixed station, the free end of said lever having movable connection with said track, and means adapted to lock such free end of said lever against movement along said track.

4. The combination with a gate of the type in question, of a track extending longitudinally of said gate, a lever pivotal about a fixed station, the free end of said lever having movable connection with said track, means adapted to lock said lever against pivotal movement when desired, and means adapted to lock such free end of said lever against movement along said track.

5. The combination with a gate of the type in question, of a track extending longitudinally of said gate, a trolley movable along said track, and a lever pivotal about a fixed station and having its free end at-

tached to said trolley, the latter being both pivotal about a vertical axis and vertically movable with respect to such lever-end.

6. The combination with a gate of the type in question, of a track extending longitudinally of said gate, a trolley movable along said track, a lever pivotal about a fixed station and having its free end attached to said trolley, the latter being both pivotal about a vertical axis and vertically movable with respect to such lever-end, means adapted to lock said lever against pivotal movement when desired, and means adapted to lock said trolley against movement along said track.

7. The combination with a gate of the type in question, of a track extending longitudinally of said gate, a trolley movable along said track, a vertical spindle on said trolley, a pedestal apart from said gate constituting a fixed station, and a lever pivotally mounted on said pedestal, said spindle being both rotatably journaled and longitudinally movable in the free end of said lever.

8. The combination with a gate of the type in question, of two propellers at each end of said gate, the axes of said propellers being inclined outwardly, at less than a right angle to the longitudinal axis of said gate.

9. The combination with a gate of the type in question, of two propellers at each end of said gate, the axes of said propellers being inclined outwardly at similar angles, less than a right angle, to the longitudinal axis of said gate.

10. The combination with a gate of the type in question, of two propellers at each end of said gate, the axes of said propellers being inclined outwardly, and means adapted to independently operate said propellers.

11. The combination with a gate of the type in question, of two propellers at each end of said gate, the axes of said propellers being inclined outwardly, means adapted to independently operate said propellers, a track extending longitudinally of said gate, and a lever pivotal about a fixed station, the free end of said lever having movable connection with said track.

12. The combination with a gate of the type in question, of two propellers at each end of said gate, the axes of said propellers being inclined outwardly, means adapted to independently operate said propellers, a track extending longitudinally of said gate, a lever pivotal about a fixed station, the free end of said lever having movable connection with said track, and means adapted to lock said lever against pivotal movement when desired.

13. The combination with a gate of the type in question, of two propellers at each end of said gate, the axes of said propellers

being inclined outwardly, means adapted to independently operate said propellers, a track extending longitudinally of said gate, a lever pivotal about a fixed station, the free 5 end of said lever having movable connection with said track, and means adapted to lock such free end of said lever against movement along said track.

14. The combination with a gate of the 10 type in question, of two propellers at each end of said gate, the axes of said propellers being inclined outwardly, means adapted to

independently operate said propellers, a track extending longitudinally of said gate, a lever pivotal about a fixed station, the free 15 end of said lever having movable connection with said track, means adapted to lock said lever against pivotal movement when desired, and means adapted to lock such free end of said lever against movement along 20 said track.

Signed by me this 26th day of July, 1920.

DAVID E. WILLIAMS.
